UNITED STATES PATENT OFFICE.

HOWARD C. FREEDENBURG, OF BALTIMORE, MARYLAND, ASSIGNOR TO THE BARTLETT HAYWARD COMPANY, OF BALTIMORE, MARYLAND, A CORPORATION OF MARYLAND.

CHARGING APPARATUS.

Application filed May 31, 1923. Serial No. 642,556.

To all whom it may concern:

Be it known that I, HOWARD C. FREEDENBURG, a citizen of the United States, residing at Baltimore, in the State of Maryland, have invented certain new and useful Improvements in Charging Apparatus, of which the following is a specification.

This invention pertains to an improved charging apparatus, the structure being designed primarily for charging the retorts of a gas producing plant with measured quantities of coal.

The main object of the invention is to provide a traveling structure carrying a storage hopper of relatively large capacity, a weighing hopper, means for discharging the weighed charge of coal into the desired retort, means, under the control of the operator, for causing a travel of the structure as a whole and means for elevating or lowering the hoppers and discharge apparatus within the supporting traveling structure so as to bring the discharging means into juxtaposition with any desired retort of the series.

The apparatus may be said to be self contained, comprising a main supporting structure or carriage capable of being moved into any desired position and carrying a storage hopper, a weighing hopper and suitable discharging mechanism, said hoppers and discharging mechanism being mounted for raising and lowering within the main supporting structure or carriage.

The apparatus is illustrated in the annexed drawings, wherein

Figure 1 is a vertical sectional view;

Figure 2 a sectional elevation at right angles to that in Figure 1; and

Figure 3 an enlarged sectional elevation of the winding drums, the gearing employed to operate the same, and the driving connections employed to traverse the carriage.

The carriage may be said to comprise a base or sub-frame 1 formed up out of suitable beams or forms secured firmly together. The frame is provided with suitable bearings 2 for the reception of axles 3 and 4 to which are secured flanged wheels 5 said wheels running on tracks 6 which extend along in front of the retorts as 7, Figure 1, which are to be charged.

Rigidly secured to and extending upwardly from the base frame is a frame denoted generally by 8 and having heavy box like girder elements 9 and 10 at the upper portion thereof, said vertical frame also including as a part thereof four vertically disposed beams or shapes 11, 12, 13 and 14. Said shapes are spaced in rectangular relation and in effect form the guides or guideway for the vertically movable hoppers and discharging mechanism.

It will of course be understood that the base frame and the upwardly extending guide and supporting frame will be substantially braced and tied together in order to sustain the load which is imposed thereon.

The storage hopper is designated by 15, the bottom being so formed that the discharge mouth 16 thereof stands more nearly adjacent the outer face or side of the guide frame than it does the inner, this to admit of the proper positioning of the delivery mechanism hereinafter described.

The mouth of the hopper is divided into a series of pocket like elements 17 the lower end of each of which is closed by a pair of gates 18 and 19 mounted upon stub axles 20 and 21 extending outwardly from the outer faces of the end walls of the pockets. The gates of each pair are provided at each end with intermeshing sector gears 22, 23 and a lever as 24 is secured to and extends upwardly from one of each pair of gates, said levers being likewise present at each end. The upper ends of the levers at one end of the gates are connected by a bar 25, while those at the opposite end of the gates are connected by a bar 26. Bar 25 is pivotally connected at one end to a lever 27, secured to a shaft 28, mounted in suitable bearings as 29, said shaft also having secured to it a lever 30. A draw bar 31 is connected to the lower end of lever 30 and extends across the structure to one side of the pockets 17. Bar 26 is connected to the rocker shaft 28 through a lever 32. It will therefore be seen that as the draw bar 31 is reciprocated the gates will be opened and closed through power applied to each end of the gates. To effect such endwise reciprocation, the bar at one end is pivotally attached to a lever 33 extending outwardly

from a collar 34, splined to and movable lengthwise of a vertically disposed shaft 35 mounted in suitable bearings and carrying at its lower end a beveled gear 36. A bevel 5 pinion 37 meshes with said gear, the pinion being secured to one end of a horizontally disposed shaft 38 while a hand wheel 39 is secured to the opposite end adjacent the operator's stand 40. By movement of the 10 hand wheel, the gates may be opened and closed as desired, to permit the desired quantity of fuel to pass into underlying weighing hopper 41.

Said hopper 41 has secured to opposite 15 sides thereof angle irons or similar supporting members denoted by 42 and 43 and to the outer end of each of these members there is secured suitable connecting elements 44 and 45 which in turn are pivotally 20 connected to the scale levers 46 and 47, the outer ends of which are in turn supported by suitable hangers 48 and 49 attached at their upper ends to a rigid built up frame member designated generally by 50. Said 25 frame member forms a guide for the upper end of the hopper 41 and is tied to and forms a part of the elevator structure proper comprising the hopper 15, the hopper 41 and the discharge mechanism hereinafter 30 described.

Levers 46 and 47 are connected at their inner ends to a scale beam or lever 51 to the outer end of which there is attached a downwardly extending link or rod 52 which in 35 turn is pivotally connected to a lever 53 fulcrumed at its inner end and having attached to its outer end a link 54, which, acting through a rocking lever 55, link 56 and a pointer 57 indicates on a dial 58 the weight 40 of the coal which is fed into the weighing hopper when the gates 18 and 19 are open. The dial 58 is located adjacent the operator's stand and he can readily determine when the proper amount or charge of material 45 has passed into the weighing hopper and through the manipulation of the hand wheel 39 can close the gates and thus cut off feed from the storage hopper or bin to the weighing hopper.

50 Secured to the lower end of the hopper 41 is a horizontally disposed guideway or track 59 upon which is mounted a truck or carriage 60 carrying a gate or valve 61 adapted to open and close the discharge mouth of 55 the weighing hopper. By reciprocating the carriage the gate valve may be opened or closed. To effect such opening and closing operation any suitable mechanism, such as the following may be employed.

60 Located to one side of the structure is a vertically disposed shaft 62 the lower end of which is mounted in a suitable bearing 63, Fig. 1, and a hand lever 64 is secured to the shaft adjacent such bearing and in 65 a position where it may be readily grasped

by the operator to oscillate the shaft. The shaft is supported and steadied by a bracketed bearing 65 secured to a fixed portion 66 of the elevator structure and encircling the shaft above said bracketed member is a 70 collar 67 which is splined for longitudinal movement on the shaft and yet partakes of the oscillating movement which may be imparted to the shaft by the operator. Extending outwardly from said collar is an 75 arm 68 which has pivotally connected to its outer end a pair of draw links or rods 69 which at their opposite ends are connected to the truck 60.

It will thus be seen that the operator may, 80 by moving the hand lever 64, effect an opening or closing of the gate 61 at the desired time.

The mouth of the hopper 41 overlies the outer end of a funnel shaped member 70, 85 said funnel having mounted therein an adjustable throat piece 71, pivoted at 72 adjacent the upper end of the front wall of the funnel. The rear wall 73 of the funnel terminates short of the lower end of the 90 funnel and the side walls extend downwardly beyond the front and rear walls and the lower ends as at 74 are of arcuate form. Secured to an axle 75, mounted in suitable 95 bearings 76 is a band or belt wheel 77. A band 78 passes about said wheel and the forward or upper run thereof closes the cut away rear portion of the funnel passing thence beneath and in contact with the edges of a relatively large pulley 79, having a 100 U-shaped channel or groove 80 formed in its periphery, over a guide pulley 81, about a second guide pulley 82 and thence rearwardly about a third guide pulley 83 back to the pulley 77. The belt as it leaves the large feed pulley 79 passes beneath the lower open portion of a pipe or conduit 84 forming in effect the bottom of said pipe, the upper wall of which at its inner end extends inwardly into the groove formed in 105 the feed pulley 79. The outer end of the pipe 84 beyond the belt is continuous, that is to say, the pipe is not cut away at its lower side at this portion. The pipe and 110 the various pulleys are supported in a sub-frame denoted generally by 85, which extends downwardly and is rigidly secured to the lower portion of the elevator structure. Motion is imparted to the belt 78 and 115 through it to the pulley 79, with which it is held in contact, from a motor 86, through a sprocket chain 87, which passes over a sprocket wheel secured to the shaft 75. The belt 78 and the pulley 79 act to gather and forward the fuel passing from the funnel 70 and to project it outwardly through the tube 84 into that retort 7, which is opposite the end of the pipe at the time the feed is 120 being effected.

As will be seen upon reference to Fig. 1 130

the pipe and the forward end of the upper run of the belt are given a slight upward inclination toward the discharge end of the pipe, this for the purpose of insuring a proper entrance of the fuel into the retort and the passage thereof to the rear portion of the retort.

To secure a raising and lowering of the elevator structure, as such, comprising the supporting frame for the storage bin, the weighing hopper and the fuel feeding and projecting means, as just described, and likewise to effect a traverse of the structure as a whole along the rails of the track 6, 15 the following means may be employed.

Mounted in suitable bearings, secured to the frame 8, is a pair of drums 86 and 87, said drums being each provided with oppositely inclined spiral winding grooves or 20 channels 88, 89 adapted to receive a pair of chains 90 and 91 for the drum 86, and 92 and 93 for the drum 87. The chains 90 and 91 pass upwardly from the drum 86 and over double rollers or sheave pulleys 94, 25 chain 90 passing over a pulley 95, thence downwardly beneath a pulley 96 secured to the lower portion of the elevator frame, thence upwardly to a fixed element 97 which is secured to the lower portion of the box-like girder 9. Chain 91 passes from pulley 94 over a pulley 98, thence downwardly under and about a pulley 99, and upwardly to a fixed element 100, likewise secured to the girder 9. Chains 92 and 93 follow the 30 same general course passing over and about similar pulleys upon the opposite side of the machine. The ends of the chains being secured to members, similar to the members 97 and 100, attached or secured to the box-like girder 10.

Secured to each of the shafts upon which the drums 86 and 87 are likewise secured, are worm gears 101, and 102, said gears meshing with worms as 103, the shafts upon 45 which said worms are mounted carrying at their outer ends bevelled gears 104 and 105 respectively. Said gears mesh with bevelled gears or pinions 106 and 107 secured upon a shaft 108, the outer end of which carries a clutch element 109.

Motion for rotating the drums and consequently raising the elevator structure is imparted to the gearing just described from a motor 110, the motor shaft carrying a 50 pinion 111, which meshes with a gear 112, secured upon a shaft mounted in a suitable bearing 113, the shaft at its other end extending freely through the hub of a pinion 114 and into and driving a shiftable clutch member 115. The pinion 114 carries a clutch element 116. The constantly driven clutch element 115 may be shifted into driving connection with the clutch element 109 through the manipulation of a hand lever 65 117 which is connected with such shiftable

clutch member through a link 118 and a lever 119. The motor will be provided with a reversing drum type controller and may therefore be operated in either direction and thus power may be applied to rotate the 70 drums to wind or unwind the chains.

Motor 110 also serves as a means for traversing the structure as a whole along the rails. Pinion 114 meshes with a gear 120 secured upon a shaft 121, a pinion 122 being attached to the other end of the shaft and meshing with a gear 123 which in turn drives a sprocket wheel 124. A sprocket chain 125 passes about the sprocket wheel 124 and about a larger sprocket 126 secured to the axle 3. When the clutch element 115 is shifted to the left it imparts its motion to pinion 114 and such motion is transmitted through gear 120, shaft 121, pinion 122, gear 123 and sprocket chain 125 to the axle 80 thus causing the structure to be moved along the tracks or rails 6. By reversing the motor traverse may be in either direction along the track so as to bring the discharge tube 84 into alignment with any vertical series of retorts or to bring the storage hopper 15 beneath a bin or similar point of supply from which the hopper 15 may be filled. Suitable brake mechanism, not shown, 85 may be employed, to arrest the travel of the carriage.

It is thought that the operation of the mechanism will be understood from the foregoing description but a brief résumé will be given.

Assuming that the storage hopper 15 has been filled, the operator starts the motor 110 and throws the clutch element 115 to the left causing the gearing just described to come into operation and bring the discharge pipe 84 into alignment with the retort to be charged. The carriage is then brought to rest by disconnecting the clutch element. The operator then, through the manipulation of the hand wheel 39 opens the gates 18, 100 19 and permits the coal to pass from the hopper 15 into the weighing hopper 41. When sufficient coal has passed into the weighing hopper, as will be shown by the indicator 57 on the dial 58, the operator 105 closes the gates 18, 19. Then by manipulating the hand lever 64, he causes a retraction of the gate 61 and permits the weighed charge to pass from the weighing hopper into the funnel 70.

The coal passes downwardly through the funnel 70 and is gathered up and carried downwardly and forwardly between the upper run of the belt 78 and the grooved pulley or wheel 79. Owing to the speed of the belt the coal will be projected forwardly and outwardly through and from the mouth of the tubular member 84 and projected into the retort with which the tube is at that time in alignment.

Having reference to Fig. 1 and assuming that the lower retort 7 has been charged, the gate 61 is closed and the operator will again start the motor 110 in operation and throw the clutch element 115 to the right whereby the drums 86 and 87 will be caused to rotate, winding the chains thereon and causing the elevator structure as a whole to be moved upwardly, the parts being brought to rest when the pipe 84 is in line with the next retort above, or in alinement with any one of the retorts which it is desired to charge. The charge is then permitted to pass from the storage hopper into the weighing hopper where it is weighed and from which it is allowed to gravitate into the funnel to be projected in the manner above described into the retort.

It will thus be seen that I have produced a charging mechanism by which the various retorts may be readily and accurately charged. The mechanism may be traversed in front of the retorts and likewise raised and lowered in order to charge the various retorts in the vertical series. The structure is self contained and is easy of manipulation and control and materially assists in the proper charging of the retorts so that each retort will receive a weighed charge to meet the conditions under which the plant is being operated.

While I have described the structure somewhat in detail, it is to be understood that in so far as the generic invention is concerned, that the same is not limited to such details and the broader claims are to be read and construed in light of this understanding.

Having thus described my invention what I claim and desire to secure by Letters Patent is:

1. In an apparatus of the character specified, the combination of a supporting frame; an elevator structure carried thereby, said structure embodying a storage hopper, a weighing hopper, and a discharging mechanism; means under control of the operator for raising and lowering the elevator structure; and means likewise under control of the operator for controlling the discharge of material from the storage hopper to the weighing hopper and from the weighing hopper to the discharge mechanism.

2. In an apparatus of the character specified, the combination of a traveling supporting frame; an elevator structure mounted within said frame and embodying a storage hopper, a weighing hopper underlying said storage hopper, and a discharge mechanism adapted to receive the material from the weighing hopper; means under control of the operator for raising and lowering the elevator structure; and means, likewise under control of the operator for controlling the passage of material from the storage

hopper to the weighing hopper and from the latter to the discharge mechanism.

3. In an apparatus of the character specified the combination of a supporting frame capable of being traversed; means for traversing the same; an elevator structure supported within the frame, and comprising a storage hopper, a weighing hopper underlying the same, and a discharge mechanism for the material underlying the weighing hopper; means controlling the passage of material from the storage hopper to the weighing hopper; means controlling the passage of the material from the weighing hopper to the discharge mechanism; and means under the control of the operator for raising and lowering the elevator.

4. In an apparatus of the character specified, the combination of a supporting frame capable of being traversed; a storage hopper; a weighing hopper located beneath the same; means controlling the discharge of the material from the storage hopper into the weighing hopper a discharge mechanism associated with and underlying said weighing hopper and adapted to project the material discharged from the hopper in a lateral direction; and means under the control of the operator, for raising and lowering the hopper and associated discharge mechanism.

5. In an apparatus of the character specified the combination of a hopper; a funnel underlying the discharge mouth of the hopper; a grooved pulley located at one side of the discharge end of the funnel; a pipe extending laterally from the lower portion of the pulley, the major portion of the lower side of the pipe being cut away; an endless belt having its upper run extending beneath the open end of the funnel, beneath and in contact with the under run of the pulley, and beneath the lower open side of the pipe; and means for driving the belt.

6. In an apparatus of the character specified the combination of a supporting frame; wheels upon which said frame is mounted; vertically disposed guides carried by the frame; a secondary frame mounted within the supporting frame and engaging the guides; a supply hopper mounted in the upper portion of the secondary frame; gates controlling the discharge of said hopper; a weighing hopper mounted in the secondary frame below the gates just mentioned; a gate for controlling the discharge of material from said weighing hopper; means under the control of the operator for actuating the gates; a funnel-shaped member standing in alinement with the discharge of the weighing hopper; a pulley having a U-shaped rim located adjacent the lower end of the hopper; an endless belt, the upper run of which extends beneath the lower end of the funnel and contacts the lower por-

tion of the pulley forming therewith a conduit for the forward feeding of the material passing from the funnel; a tubular member extending outwardly from the lower portion

5 of the pulley, the belt aforesaid forming the lower portion of said tubular member; means for driving the belt; and means under the control of the operator for raising

and lowering the secondary frame and the parts carried thereby and likewise imparting motion to the wheels upon which the supporting frame is mounted. 10

In testimony whereof I have signed my name to this specification.

HOWARD C. FREEDENBURG.
